UNITED STATES PATENT OFFICE.

HARRY A. WILLS, OF KEESEVILLE, NEW YORK, ASSIGNOR TO A. W. KINGSLAND, OF SAME PLACE.

MACHINE FOR MAKING HORSESHOES.

Specification of Letters Patent No. 29,042, dated July 3, 1860.

To all whom it may concern:

Be it known that I, HARRY A. WILLS, of Keeseville, in the county of Essex and State of New York, has invented certain new and useful Improvements in Machines for Making Horseshoes; and I do hereby declare that the following is a full, clear, and exact description of the same, reference being had to the accompanying drawing, 10 forming a part of this specification, in which—

Figure 1 represents a front elevation of my invention. Fig. 2 is a transverse vertical section of ditto, the line x, x , Fig. 1, 15 indicating the plane of section.

Similar letters of reference in both views indicate corresponding parts.

This invention consists in arranging the shaping die or mold of a cylinder machine 20 with a movable front, which when thrown forward bends the iron to the required shape and holds it in the proper position until the swaging die grips it, and then being thrown back allows the iron to spread; and it consists also in the employment of a crank 25 shaft which is subjected to the action of a spring and the bent end of which sweeps over a stationary die which is rigidly attached to the side of the frame which 30 forms the bearings for the cylinders so that at the proper intervals said front is drawn in and the iron set free.

To enable those skilled in the art to make and use my invention I will proceed to describe its construction and operation with reference to the drawings.

A, A represent the frame which forms the bearings for the cylinders B, B'. This frame is made of cast-iron or of any other 40 suitable material of sufficient strength to sustain the strain necessary for the operation of making horse shoes.

The lower cylinder B, is provided with the female die C, and a cam a , projecting 45 from its surface serves to operate the cutter b , which is attached to the curved bar D, and which in combination with the stationary cutter c , cuts off the blanks to the required length in a similar manner to the 50 machine for which a patent was granted to me on the 2nd of March 1858.

The swaging die E, is secured to the surface of the upper cylinder B', and two

curved grooves d, d' , on the sides of this die and in the surface of the cylinder B', form 55 the guides for the vibrating arms e, e' , which hold the blank after the same has been cut, and bend it around the mold or shaping die F. In bending the blank around the mold it is necessary to allow the same a 60 certain amount of play so that it can spread under the action of the swaging die, and if the iron is bent through the action of the front of said mold itself, it will lay close up to the mold or at least to the front of the 65 mold and no chance is left to the same to spread.

In order to avoid this difficulty I have made the front f , of my mold movable, and I have arranged it so that the same recedes 70 and gives to the iron room to spread under the action of the swaging die E.

The front f , is attached to an arbor g , that passes through the interior of the cylinder B'. One end of this shaft extends beyond 75 the side of said cylinder, and a crank h , is attached to it which by sweeping over a stationary cam i , on the side of the frame A, keeps the front f , up. A spring j , attached to the front f , and operating in the interior 80 of the cylinder B', has a tendency to throw the front back as soon as the crank h , is released from the cam i . This cam is furnished with a shoulder k , in passing which the crank h , is suddenly released, allowing 85 the front f , to recede through the action of the spring j , and the shoulder k , is in such a position that said front is thrown back just before the action of the swaging die on the blank begins. By these means I have ac- 90 complished in a simple and effective manner what otherwise requires a complicated machinery and at the same time the front f , can be made to project far enough so as to afford 95 a good hold on the blanks without interfering with the action of the swaging die.

After the horse shoes have been completely formed by the action of the two cylinders B, B', they are taken up by the clearer H, from whence they are removed and put 100 away in a box or in any convenient receptacle.

I do not claim broadly the employment of the movable front of the shaping die of a horse shoe machine; but

Having thus fully described my invention,

what I claim as new, and desire to secure by Letters Patent, is—

1. The arrangement of the movable front, substantially as described, when the same is used in combination with the shaping die or mold E, on the surface of the rotary cylinder B', for the purpose herein set forth.
- 5 2. The arrangement of the stationary cam

i, crank h, spring j, and front f, in combination with the shaping die or mold E, constructed and operating as and for the purpose specified.

HARRY A. WILLS.
